AERIAL TOW TARGET

Frank G. Manson and James J. Maskey,
Dayton, Ohio

Application May 6, 1941, Serial No. 392,088

7 Claims. (Cl. 273—105.3)

(Granted under the act of March 3, 1883, as
amended April 30, 1928; 370 O. G. 757)

The invention described herein may be manufactured and used by or for the Government for governmental purposes, without the payment to us of any royalty thereon.

This invention relates to a sleeve type aerial tow target, and has special reference to the construction and arrangement of the mouth end of the target, including the mouth ring and towing bridle.

An object of the invention is to provide an improved collapsible mouth ring for a sleeve target, to permit compact folding of the target to relatively small dimensions to expedite packing and handling and to facilitate launching through a restricted opening.

A particular object is to provide a folding mouth ring, comprising two semi-circular parts hinged together to fold on a diameter of the ring, for a sleeve-type target.

A further object is to provide an improved bridle for a sleeve-type target having a folding mouth ring, which will insure proper opening of the mouth ring when the target is launched from an airplane in flight.

Other objects and advantages reside in the construction of parts, the combination thereof and the mode of operation, as will become more apparent from the following description.

In the drawings:

Fig. 1 is a fragmentary side elevation view of a sleeve target constructed according to the present invention.

Fig. 2 is a plan view of the mouth ring.

Fig. 3 is a perspective view of the target prior to opening of the mouth ring, as the target is launched from an airplane in flight.

Fig. 4 is a perspective view showing one side of the mouth ring in open position as the sleeve begins to fill with air.

Fig. 5 is a perspective view showing the final stage in which the mouth ring has fully opened and the sleeve has filled with air.

Fig. 6 is a perspective view showing how the folding mouth ring may refuse to open in the air stream if the bridle does not include means for separating the two parts of the ring.

The tow target of the present invention comprises a sleeve 1 having a circular ring 2 incorporated in the mouth end thereof, for attachment of a towing bridle and to keep the sleeve open and filled with air in flight. One of the principal features of novelty is the construction of the ring 2 so as to fold to smaller dimensions to expedite packing and handling, and to permit

launching through a restricted opening. The ring 2 comprises a pair of similar semi-circular parts 3 and 4 having diametric elements 5 and 6 disposed in side-by-side relation in the manner illustrated. Stiffening struts 7 may be provided to add rigidity to the ring. To permit folding the two parts 3 and 4 one upon the other, hinge means are provided on the diametric elements 5 and 6. This hinge arrangement has been conveniently constructed in the present embodiment of strap loops 8 welded to the element 6 so as to loosely encircle the element 5, thus providing free pivotal motion of the part 3 upon the part 4. Projections 9 are provided on the element 5 for preventing longitudinal movement of the element 5 in the strap loops 8.

The folding ring above described is incorporated into the circular mouth of the target sleeve 1, preferably by inclosing the ring within a stitched fold in the material of the sleeve. The ring is thereby adapted to hold the mouth of the sleeve in the form of a circular opening and to provide a rigid marginal portion for attachment of the bridle ropes. In the present embodiment, this means of attachment comprises grommets 10 and 11 located at intervals around the margin of the circular opening. This specific means of attachment forms no part of the present invention and may take any other form suitable for attachment of the bridle ropes, either to the fabric of the sleeve or to the ring 2 itself. In the preferred embodiment there are a pair of grommets 11 adjacent each of the struts 7 so that a loop of each bridle rope may be passed through each pair of grommets in the manner shown.

Thus there is a bridle rope 12, 13 leading from each junction of a strut 7 with the ring 2 to a towing line attaching ring or eye 15. A pair of grommets 10 are also provided adjacent the junction of the diametric members 5 and 6 with the parts 3 and 4 respectively, at the folding points of the ring. These last mentioned grommets secure the ends of a pair of bridle ropes 16, which terminate at their other ends in the ring or eye 15. The bridle ropes 16 are similar to the bridle ropes 12 and 13 except that they are connected by a transverse rope member 17 at points a distance of about half the ring radius ahead

50 of the grommets 10.

The specific arrangement of the bridle described above constitutes an additional feature of novelty designed to insure proper inflation of the target by separating the folding parts of the mouth ring 55 to form a circular opening in the air stream.

This is accomplished by reason of the fact that the transverse member 17 is of a length just sufficient to span the bridle ropes 16 when they are tensioned by the towing line, which length is seen to be somewhat less than the diameter of the ring 2, thereby constraining the member 17 to lie between the two parts 3 and 4 of the folding ring when the latter is folded like a purse in the packing and folding of the sleeve. By maintaining the member 17 always between the parts 3 and 4, tension upon the ring 15 in launching the target will separate the parts 3 and 4 sufficiently to engage the air stream so as to inflate the sleeve. Without the member 17, it is sometimes found in launching the target that the bridle ropes will all lie outside of the folded members 3 and 4, being disposed on one side of the ring in such a manner as to prevent the proper inflation of the sleeve by the air stream.

Figures 3, 4 and 5 represent successive stages in the opening of the sleeve target after it is launched from an airplane in flight. When the folded target is caught in the air stream, the tension exerted upon the eye 15 immediately pulls the ropes 16 taut, allowing the material of the sleeve 1 to unfold, the semicircular parts 3 and 4 for the moment being considered to be still in their folded position, one against the other, allowing the ropes 12 and 13 to slacken as shown. It will be appreciated, however, that the parts 3 and 4 will not remain tightly together, since they are separated by the member 17, which is constrained to occupy the position illustrated. From the momentary condition illustrated in Figure 3, one or the other of the parts 3 or 4 will be immediately opened to its fullest extent by the pressure of the air stream, as illustrated in Figure 4 where it is assumed that the part 3 has been blown open, leaving the part 4 still in the position assumed in Figure 3. The swinging movement of the part 3 will be arrested as the ropes 12 are pulled taut, whereupon the plane of the part 3 will be substantially normal to the line of flight. It will be clearly seen in Figure 4 that the member 17 positively prevents the part 4 from following the part 3 into a plane at right angles to the direction of flight.

In the position of Figure 4, the sleeve 1 will rapidly fill with air and draw open the part 4, if this part has not already opened simultaneously with the part 3. Figure 4, therefore, like Figure 3, represents an unstable condition which cannot be maintained in flight. Figure 5, then, represents the fully opened position of the two parts 3 and 4 of the mouth ring, establishing a circular opening at the leading edge of the sleeve 1 as is desired to be maintained in steady flight.

Figure 6 illustrates an undesirable situation which is found to occur if the transverse member 17 is omitted. The mouth ring and the bridle in Figure 6 correspond to the mouth ring and bridle described above, except for the omission of the member 17. While the bridle shown in Figure 6 will often produce a proper opening of the sleeve, it is found in practice that occasionally, instead of opening, the part 4 will be blown around with the part 3 into a plane more or less normal to the line of flight, the air pressure upon the sleeve material attached to the part 4 holding the said part 4 tightly against the part 3 with the ropes 13 substantially as taut as the ropes 12 and 16. When the parts assume this position they remain so in the air stream, with the result that the target may be towed

indefinitely without opening the mouth ring and inflating the sleeve.

It will be appreciated that the provision of the transverse member 17 would positively prevent the part 4 from passing between the bridle ropes 16 to assume the position illustrated in Figure 6. With the member 17 connecting the ropes 16, any air flow condition which might tend to produce the situation shown in Figure 6 could in fact do no more than momentarily hold the part 4 in a plane parallel with the line of flight, as in Fig. 4, which, as stated above, has been found to be an unstable position due to the inflation of the sleeve through the open half of the ring. When the condition of Fig. 4 occurs, the ring immediately opens to the position shown in Fig. 5. The present invention thus not only provides a folding mouth ring for compact folding of a sleeve target, but in addition prevents objectionable fouling of the bridle ropes, and insures the proper opening and inflation of the sleeve, even when packed and launched by inexpert persons.

While we have shown and described but a single embodiment of our invention, it is to be understood that it is capable of many modifications. Changes, therefore, in the construction and arrangement may be made which do not depart from the spirit and scope of the invention as defined in the appended claims.

We claim:

1. In a sleeve type aerial tow target, a folding circular mouth ring comprising two semi-circular parts hinged together to fold on a diameter of the ring, and a bridle for towing said target, said bridle comprising a plurality of bridle ropes attached at intervals around the ring and converging to a common point of attachment with a tow line, two of said bridle ropes being attached to the ring at the folding points, and a transverse rope member connecting said two bridle ropes at the approximate distance of half the ring radius ahead of their attachments with the ring, said transverse rope member having a length less than the diameter of said ring.

2. In a sleeve type aerial tow target, a folding circular mouth ring comprising two semi-circular parts hinged together to fold on a diameter of the ring, and a bridle for towing said target, said bridle comprising a plurality of bridle ropes attached at intervals around the ring and converging to a common point of attachment with a tow line, two of said bridle ropes being attached to said ring at the folding points, and a transverse member connecting said two bridle ropes so as to lie between said parts when the latter are folded together.

3. In a sleeve type aerial tow target, a folding circular mouth ring comprising two semi-circular parts hinged together to fold on a diameter of the ring, and a bridle for towing said target, said bridle comprising a plurality of bridle ropes attached at intervals around the ring and converging to a common point of attachment with a tow line, two of said bridle ropes being attached to the ring at the folding points, and means associated with said two bridle ropes to insure separation of the two parts of the mouth ring when the target is launched from an airplane in flight.

4. In a sleeve type aerial tow target, a folding circular mouth ring comprising two semi-circular parts hinged together to fold on a diameter of the ring, and a bridle for towing said target, said bridle comprising a plurality of bridle ropes at-

tached at intervals around the ring and converging to a common point of attachment with a tow line, and means on said bridle to insure separation of the two parts of the mouth ring when the target is launched from an airplane in flight.

5. In a sleeve type aerial tow target, a folding circular mouth ring comprising two semi-circular parts hinged together to fold on a diameter of the ring, and a bridle attached to said ring, said bridle having a part thereof constrained to lie between said parts of said ring when said ring is folded, to insure separation of the two parts of said ring and proper opening of the sleeve when the target is launched from an airplane in flight.

6. A bridle for a sleeve type aerial tow target having a folding mouth ring, comprising a plu-

rality of bridle ropes adapted for attachment at intervals around the mouth of said sleeve and converging to a common point of attachment with a tow line, and a transverse member connecting two opposite ones of said bridle ropes to insure proper opening of said folding ring and inflation of said sleeve when the target is launched from an airplane in flight.

7. In a sleeve type aerial tow target, a folding circular mouth ring comprising a pair of semi-circular parts, each part having a diametric element integral therewith, and hinge means connecting said two elements for folding one of said parts back upon the other part.
